UNITED STATES PATENT OFFICE.

PAUL H. MEINHART, OF MARION, OHIO.

ROCKER ATTACHMENT.

1,227,062.

Specification of Letters Patent. Patented May 22, 1917.

Application filed December 23, 1913. Serial No. 808,404.

To all whom it may concern:

Be it known that I, PAUL H. MEINHART, a citizen of the United States, residing at Marion, in the county of Marion and State 5 of Ohio, have invented certain new and useful Improvements in Rocker Attachments; and I do hereby declare the following to be a full, clear, and exact description of the invention, such as will enable others skilled 10 in the art to which it appertains to make and use the same.

My invention relates to new and useful improvements in rockers and more particularly to an attachment therefor which consists of cushioning means adapted to be secured to the tread portion of the ends of the rocker.

An important object of my invention is to provide an attachment of the character 20 which when secured to the tread portion of a rocker adjacent each end thereof, prevents jarring incident to rocking of the chair and provides an even rocking action.

Another important object is to provide an 25 attachment of the character described which is extremely simple as to construction, which may be readily attached to rockers of all kinds, and which is cheap to manufacture.

The above and additional objects are accomplished by such means as are illustrated 30 in the accompanying drawings, described in the following specification and then more particularly pointed out in the claim which is appended hereto and forms a part of this 35 application.

With reference to the drawings, wherein I have illustrated the preferred embodiment 40 of my invention as it is reduced to practice, and throughout the several views of which similar reference numerals designate corresponding parts.

Figure 1 is a side elevation of a portion 45 of a chair showing the legs and rocker thereon with my attachment in position on the rocker,

Fig. 2 is a bottom plan view of my attachment, and

Fig. 3 is a longitudinal sectional view 50 taken through my attachment showing the detail construction thereof and the arrangement of washers in each end to facilitate rigid securing of the attachment.

Referring to the drawings by characters 55 of reference, 1 designates my attachment as an entirety which is adapted to be secured adjacent each end of the tread portion of a

rocker 2 by screws or other suitable fastening means.

The attachment 1 consists of an elongated piece of suitable rubber being tapered toward one end as at 3 and provided at its larger end with an enlarged approximately circular offset portion 4. Embedded within the offset portion 4 is an annular washer 5. An opening 6 is formed centrally through 60 the portion 4 and the opening in the washer 5 registers with the opening 6. Suitable fastening means may be inserted through the opening 6 and washer 5 and is held against accidental withdrawal by its engagement 65 with the washer 5 which serves to reinforce the portion 4.

The smaller end of the attachment 1 is provided with an opening 7 and an embedded washer 8 similar to the one 5. Suitable 75 fastening means not shown is adapted to be inserted through the opening 7 for the purpose of securing the attachment 1 to the rocker 2.

To attach the attachment 1 to the rocker, 80 two of the attachments 1 are arranged longitudinally of the rocker 2 adjacent each end of the tread portion thereof and so that the enlarged portion 4 of each attachment is outermost with respect to the ends of the 85 rocker 2, and the securing means is then inserted through the openings 6 and 7 in the attachments for the purpose of securing the attachment to the rocker.

The cushions are secured to the treads of 90 the rockers in spaced relation to the points of normal contact of treads with the floor, so that under normal conditions the weight of the chair or its and an occupant's weight are not borne by the cushions, which weight 95 or weights would if normally borne by the cushion soon destroy the elastic or cushioning qualities. This arrangement of the cushions also permits the chair to be rocked in both directions by limited degrees, before 100 the cushions are brought into play, and permits the chair to be freely slid from place to place without being retarded by the cushioning members coming in contact with the floor. The cushions increase in thickness 105 from their inner to their outer ends so that their elasticity of cushioning action will increase by the rocking in direct proportion to the increase in the degree of rocking of the chair. The enlarged heads at the outer ends 110 of the cushions serve to limit the rocking of the chair in both directions.

It will thus be apparent with reference to the foregoing description and accompanying drawings that there has been provided an article of manufacture consisting of an attachment for rockers which is cheap to manufacture, simple as to construction and which is capable of being readily attached to rockers of all characters.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.

What is claimed is:—

In combination, a rocker, a pair of elongated cushion members secured to the oppo-

site ends of the tread of the rocker in spaced relation to the point of normal contact of the tread with the floor, each cushion including an elongated body tapering from its inner to its outer end and having an enlarged circular head formed on the under side of its outer end, the inner end of each of said cushioning members being at a point spaced from the normal contact of the tread with the floor thus permitting the chair to be moved about over the floor without lifting the same bodily therefrom, said enlarged outer ends of each gripping member permitting the elasticity of the cushioning action to be gradually developed when rocking the chair and also serving to limit the rocking motion of the chair in either direction to prevent the same from being tilted over.

In testimony whereof I affix my signature in presence of two witnesses.

PAUL H. MEINHART.
